UNITED STATES PATENT OFFICE

128,494

DESIGN FOR A BRACELET OR SIMILAR ARTICLE

Herbert Z. Lerner and Fred Goldsmith, Jr.,
Memphis, Tenn.

Application May 12, 1941, Serial No. 100,910

Term of patent 3½ years

To all whom it may concern:

Be it known that we, Herbert Z. Lerner and Fred Goldsmith, Jr., both citizens of the United States, residing at Memphis, in the county of Shelby and State of Tennessee, have invented a new, original, and ornamental Design for a Bracelet or Similar Article, of which the following is a specification, reference being had to the accompanying drawing, forming part thereof.

We claim:

The ornamental design for a bracket or similar article, as shown.

H. Z. LERNER.
